Primary Examiner — Darlington Ly*Assistant Examiner* — Nasim Abdulaziz Ali(74) *Attorney, Agent, or Firm* — Che-Yang Chen; Law Office of Michael Chen**CLAIM**

The ornamental design for a bicycle, as shown and described.

DESCRIPTION

FIG. 1 is a perspective view of the bicycle showing my new design;

FIG. 2 is a front elevational view thereof;

FIG. 3 is a rear elevational view thereof;

FIG. 4 is a left elevational view thereof;

FIG. 5 is a right elevational view thereof;

FIG. 6 is a top plan view thereof; and,

FIG. 7 is a bottom plan view thereof.

The broken lines depict portions of the bicycle that form no part of the claimed design.
